UNITED STATES PATENT OFFICE

NELS G. ANDERSON, OF SPRINGFIELD, OHIO, ASSIGNOR TO INTERNATIONAL HAR-
VESTER COMPANY, A CORPORATION OF NEW JERSEY

HOOD FASTENER

Application filed October 8, 1927. Serial No. 224,843.

This invention relates to a latch fastening device for use with the hoods or bonnets which cover the engines of motor vehicles to hold the door members of such hoods 5 latched in their closed positions.

The main purpose of the invention is to fasten the bonnet or hood doors of a motor vehicle in position in such manner as to minimize rattling and vibration of the said 10 doors against adjoining structures.

Another important purpose of the invention is to provide an improved hood door latch fastener which will be simple in construction and effective for the purpose for 15 which it was designed, and which fastener may be readily manufactured at low cost.

Briefly, these desirable objects are accomplished in a latch comprising a main latch part pivotally connected to a spring pulled 20 anchor part, in such a manner, that the latch part may engage a stop part on the hood door, while the spring exerts a downward and inward pull on a line passing diagonally through the vertical side of the hood to press 25 the hood, or door yieldingly against an adjoining abutment on the frame of the vehicle, thereby preventing slamming of the door and the noise incident to slight movements 30 of the edges of the door against and away from the abutment mentioned.

An embodiment of the invention is set forth in the accompanying drawing, but it is to be understood that the construction therein disclosed is for the purpose of illustration only and not as defining the limits 35 of the invention.

In the drawing, the figure is a side view showing a section through the vehicle frame and hood door in combination with the improved fastener of this invention.

Referring to the drawing, the vehicle frame is shown at 1, carrying a sill support 2 having an upright abutment 3 and an in- 45 wardly projecting skirt portion 4. The abutment is provided with an elongated vertical opening 5 indicated by the dotted lines. The hood door is shown at 6, its lower end being formed with a portion 7 adapted to abut 50 against the abutment 3. Above the portion

7 the door is provided with a catch 8. This catch is preferably of spring material.

Inside the hood the skirt portion 4 slidably carries an anchor member in the form of an eye bolt 9 having an enlarged eye 10 above the portion 4. Below the portion 4 the bolt carries an encircling spring 11 held against a washer 12 fixed to the bolt by a pin 13. This spring normally pulls the anchor member and holds it in its down po- 55

sition.

Outside the hood is a latch member 14 having a handle 15 whereby it may be operated, and a hook portion 16 adapted to hook over the catch 8 on the door. The latch 14 includes an integral, transversely extending, angular part 16 protruding through the opening 5 in the abutment 3. The part 17 is pivotally connected, as shown, to the eye 10 of the bolt 9 inside the hood. 60

In latching position, as shown in the drawing, the door 6 is held down and against the abutment 3 by the latch 14, the hook 16 of which bears down on the catch 8. As this catch 8 is springy the door 6 is caused to be flexed inwardly, thereby yieldingly but securely keeping the door against the abutment 3. The spring pressed anchor bolt 9 exerts a down pull on the latch part 14 to keep 65 the parts in latched position.

When it is desired to release the latch to permit opening of the door 6, it is merely necessary to grasp the handle 15 and pull up on the latch 14 against the pull of the spring 11 to release the hook 16 from the catch 8, whereupon the latch 14 may be pivoted out and down to free the door and permit its opening in the usual way. 70

It can now be seen that an improved device of the kind described has been provided, which achieves all of the desirable objects heretofore recited. 75

What is claimed is:

1. In a hood door fastener, a support ad- 80
jacent the edge of the door, an anchor mem-
ber on the support, said anchor member com-
prising a spring pulled eyebolt inside the
hood, a catch on the door, and a latch member
pivotally mounted in the eye of the anchor 85
100

- member and engageable with the catch to hold the door against the support.
2. In a hood door fastener, a support adjacent the door edge, said support comprising an abutment and a skirt projected inside the hood, an anchor member slidably carried in the skirt, a catch on the door, and a latching handle part pivotally connected to the anchor member and engageable with the catch to hold the door against the abutment.
- 10 3. In a hood door fastener, a support adjacent the door edge, said support comprising an abutment and a skirt projected inside the hood, a spring pulled eyebolt anchor slidably carried in the skirt, a catch on the door, and a latching handle part pivotally mounted in the eye of the anchor, said latching handle having a hook engageable with the catch to hold the door against the abutment.
- 15 4. In a hood door fastener, a support including a abutment adjacent the edge of the door, an anchor member slidably carried by the support, a catch on the door, and a latching handle member having a hook part engageable with the door catch, said latching handle embodying an angularly related transverse portion passed through a vertical slot in the abutment for vertical movement and
- 20 pivotally connected to the anchor member inside the hood.
5. In a hood door fastener, a support including an abutment adjacent the edge of the door, an anchor member carried by the support, said anchor member comprising a spring pulled eyebolt, a catch on the door, and a latching handle member having a hook part engageable with the door catch, said latching handle embodying an angularly related transverse portion passed through a slot in the abutment and pivotally connected to the eye of the anchor member.
- 25 6. In a hood door fastener, a support including an abutment adjacent the door edge, an anchor carried by the support inside the hood, a latching handle including a hook, said handle being pivotally connected to the anchor, and a spring catch on the door, whereby the hook on the handle may engage the
- 30 spring catch to hold the door and cause the spring catch to yieldingly press the door against the abutment.

In testimony whereof I affix my signature.
NELS G. ANDERSON.
